CLAIM

The ornamental design for a display screen or portion thereof with a graphical user interface for a machine-readable label, as shown and described.

DESCRIPTION

The FIGURE is a front view of a display screen or portion thereof with a graphical user interface for a machine-readable label showing the design.

The dashed-dotted broken lines illustrate a display screen or portion thereof and form no part of the claimed design. The dashed broken lines illustrate portions of the graphical user interface for a machine-readable label that form no part of the claimed design. The stippled shading forms no part of the claimed design.
